UNITED STATES PATENT OFFICE

106,598

DESIGN FOR A COMBINATION CIGARETTE BOX AND ASHTRAY

Arnold I. Lorenzen, Toledo, Ohio

Application September 11, 1937, Serial No. 71,562

Term of patent 14 years

To all whom it may concern:

Be it known that I, Arnold I. Lorenzen, a citizen of the United States residing at Toledo, in the county of Lucas and State of Ohio, have invented a new, original, and ornamental Design for a Combination Cigarette Box and Ashtray, of which the following is a specification, reference being had to the accompanying drawing forming a part thereof.

In the drawing:

Fig. 1 is a perspective view of a combination cigarette box and ashtray showing my new design.

Fig. 2 is a side elevational view thereof.

I claim:

The ornamental design for a combination cigarette box and ashtray substantially as shown.

ARNOLD I. LORENZEN.
